TRANSMITTER

Frederick Charles Lunnon, Chelmsford, England,
assignor to Radio Corporation of America, a
corporation of Delaware

Application March 6, 1931, Serial No. 520,587,
and in Great Britain March 20, 1930

5 Claims. (Cl. 250—17)

This invention relates to keying arrangements for use in high frequency circuits. More particularly the invention relates to keying arrangements of the so-called absorber type, i.e. to arrangements in which a transmitter, which is keyed, is kept under load during "spacing" periods by means of one or more thermionic tubes which are arranged to provide a load upon the source of anode potential when the transmitter

10 is set to "spacing".

According to this invention so-called absorber keying is effected by utilizing as an absorber tube during "spacing" periods a tube which during "marking" periods functions as an amplifier.

15 The invention is illustrated in the diagrammatic drawing accompanying the specification which shows an arrangement of oscillator and three stage cascade amplifier, in accordance with the present invention.

20 Referring to this drawing, 0 represents an oscillator tube whose output circuit includes the usual fundamental oscillating circuit and is coupled through the customary coupling condenser to a first amplifier tube V1. The coupling

25 condenser is indicated at k1. The grid circuit of the tube V1 contains a resistance R1 in series with a blocking condenser Bk1. The output circuit of the tube V1 contains the usual neutralized tuned circuit and is coupled to a second ampli-

30 fier tube V2 which is in turn coupled to a third amplifier tube V3. As will be seen the circuit arrangement of the tubes V1, V2, V3 is similar, like parts being indicated in the drawing by like reference numerals provided with suffixes appro-

35 priate to the number of the stage concerned. At B is connected a source of anode potential which is common to all the tubes. X1, X2 and X3 represent series resistances which may, if desired, be provided for reducing the amplitudes of the

40 potentials applied from the source B to the anodes of the earlier stages. It is, of course, not necessary that there be a common anode source nor is the provision of resistances X1, X2, X3 an essential.

45 The negative terminal of the source of anode potential is connected through a resistance Z to the common cathode connection and a key K shunted by a condenser as shown is connected across the said resistance Z. The grid circuits

50 of the amplifier tubes are completed as shown to tapping points P1, P2 and P3. The adjacent terminals of the devices R1 and Bk1, R2 and Bk2, R3 and Bk3 are connected to the points P1, P2 and P3 respectively of the resistance Z.

55 It will be observed that the grid circuit of the

oscillator 0 contains a resistance R0 and a capacity Bk0 arranged in similar manner to the corresponding parts of the amplifiers, the grid circuit of the said oscillator being connected to a tapping point P0 on resistance Z.

60 It will be seen that when the key K is open the anode currents of the stages will flow through the resistance Z and the various grids will therefore be biased negatively by virtue of the voltage drop in the said resistance Z, the amounts of negative 65 bias depending on the current flow, the value of Z, and the positions of the various tapping points. The arrangement may be such that when the key is open the negative bias applied to the grid of the oscillator 0 is sufficient to stop oscillations 70 with the result that the driving voltage is removed from the grids of all the subsequent stages. Preferably the arrangement is such that when the key is open the negative bias applied to the grid of one of the intermediate stages is sufficient 75 to reduce the input of that stage to zero thus removing the driving voltage from subsequent stages, whilst leaving the master oscillator and the previous stages (if any) functioning. It will be observed however that in both stage ar- 80 rangements anode current continues to flow in the stages subsequent to that at which the negative grid bias is applied and the power represented by this current at the effective anode potential is of course dissipated in the tubes in 85 question.

90 The amount of this "dead loss" anode current in each stage is controlled by the negative grid bias derived from the resistance Z which is in turn determined by the value of the said resist- 95 ance and the position of the appropriate tapping points. For best results these variables should be so adjusted that the power dissipated in the tubes of each stage is as great as can be permitted. In general the power which may be allowed 100 to be taken by each stage when the key is open will be about 25% of that taken when the key is closed. The output from the source of anode potential B will therefore alternate during keying from full load to about 25% of full load. It will 105 therefore be observed that during keying there is no discontinuity or interruption from the source B so that the transit time of the key need not be considered. This feature will be found of par- 110 ticular advantage when the source of potential B is constituted by a direct current generator or by rectified and smoothed alternating current and in such cases greatly improved voltage regulation and increased factor of safety will result as compared with most known methods of key-

ing. A substantial advantage of the invention lies in the fact that the only additional apparatus required for effecting absorber keying is the resistance Z and (of course) the key.

- 5 In cases in which a plurality of sources of anode potential is employed the negative terminals of all the sources shall be connected together and then through the common resistance Z to the common cathode connection.
- 10 A method of predetermining the value of the resistance Z so that the valve in each stage subsequent to the one that is "cut off" will set itself at that point in its characteristic at which it dissipates as absorber its maximum permissible anode loss will be understood from the following example.

15 Consider the case in which the oscillator stage 0 is that which is to be "cut off" when the key is opened, i. e. the driving voltage is to be removed from the grids of the subsequent stages V1, V2, V3. Let the permissible anode loss in the stage 20 V1, V2, V3 be respectively v_1 , v_2 , v_3 watts. If the anode potential be V_B then for the stage V1 the current which can be allowed to flow during spacing periods is

$$\frac{v_1}{V_B}$$

25 Similarly with tubes V2, V3 the permissible current will be

$$\frac{v_2}{V_B}$$

and

$$\frac{v_3}{V_B}$$

30 Thus when the key is open the total current through the resistance Z will be

$$40 \frac{v_1 + v_2 + v_3}{V_B}$$

35 Let v_{1g} , v_{2g} , v_{3g} be the negative bias potentials required to set tubes V1, V2, V3 respectively at the points on their characteristics at which the plate current at no signal and at anode potential V will be

$$\frac{v_1}{V_B}, \frac{v_2}{V_B}, \frac{v_3}{V_B}$$

40 respectively. Suppose the potential v_{1g} be the greatest of these three values of negative bias potential. Then the value of Z required is

$$50 v_{1g} \times \frac{V_3}{v_1 + v_2 + v_3}$$

45 and the grid of the first amplifier stage should be connected to the negative end of the resistance Z. The grids of the two subsequent stages should be tapped on to Z at points such that the ratio of the resistance between the tapping point in question and the common cathode connection to the whole resistance will be in the case of the second amplifier

$$\frac{v_{2g}}{v_{1g}}$$

55 and in the case of the third amplifier

$$\frac{v_{3g}}{v_{1g}}$$

60 The grid of the master oscillator should be tapped on to the resistance Z at such a point that the negative potential between that point and the common cathode connection when the ampli-

fier stages are taking the above plate current is sufficient to stop oscillations.

65 The above method of calculation ignores the fact that the anode potential when the key is open is less than the value V_B by the voltage drop across the resistance Z and also ignores the voltage drops in the devices X1, X2 and X3. In practice however the said above calculation is sufficiently accurate for most cases.

Having thus described my invention and the 85 operation thereof, what I claim is:

1. Signaling means comprising a thermionic oscillator, a plurality of thermionic amplifiers coupled to said oscillator, an impedance included in a portion of a circuit which is common to the anode circuits of said oscillator and said amplifiers, means for deriving bias potential for said oscillator and said amplifiers from voltage drop occurring in said impedance and keying means in shunt with said impedance, the impedance being such that in one position of the keying means the bias applied to the oscillator is sufficient to stop oscillation so that the driving voltage is removed from the input electrodes of the amplifiers. 95

2. Signaling means comprising a thermionic oscillator, a plurality of thermionic amplifiers coupled in cascade and to said oscillator, an impedance included in a portion of a circuit which is common to the anode circuits of said oscillator and said amplifiers, means for deriving bias potential for said oscillator and said amplifiers from voltage drop occurring in said impedance, and keying means in shunt with said impedance, the impedance being of such a value that in 105 one position of the keying means the bias applied to one of the initial amplifiers coupled to said oscillator is brought to a value to render said amplifier inoperative whereby driving voltage is removed from subsequent amplifiers. 110

3. A signaling arrangement comprising a thermionic tube oscillator, a plurality of cascade connected thermionic tube amplifiers coupled to said oscillator, anode circuits for said oscillator and amplifiers, said anode circuits having a common portion, a resistance included in said common portion, connections tapped to said resistance, said connections being connected to the grid electrodes of said oscillator and said amplifiers to apply bias to the grids of said oscillator and amplifiers, and a key in parallel with said resistance. 125

4. A transmitter arrangement comprising an oscillation generator including, a thermionic tube, a plurality of thermionic tubes connected therewith, energizing circuits connected between the output electrodes of the tube in said oscillation generator and the output electrodes of each of said second mentioned tubes, said energizing circuits having a portion in common, an impedance common to said energizing circuits, a key connected in shunt to said impedance, and connections between the control electrodes of said tubes and points on said impedance, such as to cause said oscillator to develop oscillations and said tubes to act as amplifiers of the oscillations generated by said generator when said key is closed and to bias said oscillator to cut-off while permitting said amplifiers to draw a predetermined amount of energy from said source when said key is open. 140

5. A circuit for improving the power regulation of signalling devices comprising, a plurality of relaying tubes of the termionic type connected in cascade and adapted to supply oscil- 150

lating energy to a load circuit, the intensity of which energy is modulated at signal frequency comprising, direct current energizing circuits connected between the output electrodes of said tubes, said circuits having a portion in common, an impedance in said common portion, modulating means connected with said impedance for varying or modulating the amount of energy flowing in said impedance at signal frequency, 10 thereby varying the amount of oscillating en-

ergy supplied to said load circuit, and circuits to connect the control grids of said tubes to selected points on said impedance to derive therefrom potentials such that all of said tubes are operative when signals are impressed on said impedance, and such that some of said tubes are rendered inoperative and the operativeness of the remainder of said tubes decreased when no modulations are impressed on said impedance
